UNITED STATES PATENT OFFICE.

ROBERT SPENCER, OF SOUTH ORANGE, NEW JERSEY.

DESIGN FOR A TANKARD.

48,993.

Specification for Design.

Patented May 2, 1916.

Application filed March 10, 1916. Serial No. 83,440. Term of patent 7 years.

To all whom it may concern:

Be it known that I, ROBERT SPENCER, a citizen of the United States, residing at South Orange, in the county of Essex, State of New Jersey, have invented a new, original, and ornamental Design for Tankards, of which the following is a specification, reference being had to the accompanying drawing, forming a part thereof.

In the drawing, Figure 1 is a front elevational view of a tankard showing my design. Fig. 2 is a perspective view of the tankard shown in Fig. 1.

Copies of this patent may be obtained for five cents each, by addressing the "Commissioner of Patents, Washington, D. C."

The tankard illustrated is one that is particularly adapted for use in what is known in the trade as a fire lighter.

I claim—

The ornamental design for a tankard, as shown.

ROBERT SPENCER.

In the presence of—

M. F. KEATING,
EDWIN A. PACKARD.
